(**) Term: **14 Years**

(57) **CLAIM**

(21) Appl. No.: **29/132,144**

What is claimed is the ornamental design for the abrasive
resistant open cell seabed block, as shown and described.

(22) Filed: **Nov. 2, 2000**

DESCRIPTION

(51) LOC (7) Cl. **99-00**

FIG. 1 is a perspective view of the abrasive resistant open
cell seabed block;

(52) U.S. Cl. **D99/99**

FIG. 2 is a top view of the abrasive resistant open cell seabed
block;

(58) Field of Search D99/99; D13/153,
D13/156; 174/138 F, 71 R, 92, 101.5; D12/316;

FIG. 3 is a bottom view of the abrasive resistant open cell
seabed block;

D22/146; 405/15, 35; 441/44, 133; 138/103,
162; 114/266, 352; 43/44.91; D23/258

FIG. 4 is a front view of the abrasive resistant open cell
seabed block, both front and back of the block being
identical; and,

D. 196,402 * 9/1963 Brown D12/316

FIG. 5 is a right-side view of the abrasive resistant open cell
seabed block, both right and left sides of the block being
identical.

D. 219,626 * 12/1970 Breuce D99/99

D. 220,136 * 3/1971 Wilson D12/316

2,395,892 * 3/1946 Lontz 441/133
